UNITED STATES PATENT OFFICE.

RICHARD J. PRETTIE, OF WORCESTER, MASSACHUSETTS, ASSIGNOR TO THE AEOLIAN COMPANY, A CORPORATION OF CONNECTICUT.

MECHANICAL MUSICAL INSTRUMENT.

No. 893,263.

Specification of Letters Patent.

Patented July 14, 1908.

Application filed June 28, 1907. Serial No. 381,192.

To all whom it may concern:

Be it known that I, RICHARD J. PRETTIE, a citizen of the United States, and resident of Worcester, Worcester county, Massachusetts, have invented certain new and useful Improvements in Mechanical Musical Instruments, of which the following is a specification accompanied by drawings.

My invention relates to pneumatically actuated mechanical musical instruments, whether operated by pressure or suction, the particular form shown in the present application being operated by air under pressure. As is usual in instruments of this class, the air is admitted to the pneumatic key-actuating devices through a properly perforated music sheet. When a single bank of keys is to be operated these music sheets are provided with perforations—usually fifty-eight in number, one from each key-actuating device. It is, however, sometimes desired to operate more than one bank of keys from music sheets of the customary width, in co-operation with a trackerboard of the same width, in which case both the music sheet and trackerboard are provided with the requisite additional perforations. In order that this additional number of perforations in the music sheet may be used, they must be made of less area than those used when only a single bank of keys is operated, and must, it is evident, be arranged in such relation that when the single bank music sheet is used the perforations thereof will not register with any of those provided, in the trackerboard, for the additional bank or banks of keys. It has, however, been found in practice that certain difficulties arise with an instrument arranged in the manner above described, due to the insufficient venting of the space behind the valve controlling device, and it is the purpose of the present invention to remedy these difficulties. I attain this purpose by the mechanism illustrated in the accompanying drawings in which

Figure 1 is a sectional elevation showing my vent controlling apparatus arranged for use with a music sheet intended to operate two banks of keys. Fig. 2 is a similar view showing the apparatus arranged for use with a music sheet having a single set of openings. Fig. 3 is a front view of the music sheet provided with two sets of perforations, a portion being cut away to show the trackerboard. Fig. 4 is a front view of the apparatus when

using a music sheet having a single set of perforations, to coöperate with a trackerboard having a double set of perforations.

In the drawings A designates a box or casting forming a closed pressure chamber, to which air is admitted under pressure in the usual way. In this chamber is mounted a trackerboard B, provided with a double set of perforations, shown as arranged in two lines in staggered relation to each other, though they may, of course, be otherwise arranged, as, for example, side by side. All that is essential is that one set of perforations shall be so arranged that the perforations in the single bank music sheet shall register with this set only and not with the perforations of the second set.

D is a music sheet arranged to be unwound and rewound over drums in the usual way, and provided with a double set of perforations, which may be either sets of holes or slots, for operating a two bank instrument, and E (Figs. 2 and 3) is a music sheet having as usual only one set of perforations.

Each set of holes in the trackerboard is connected by tubing F, G, to conduits H, I, in the valve boxes J. Each of these valve boxes has a pressure chamber K, in the bottom of which is a passageway for each of a series of notes in which is mounted a double-acting valve L, carried by a diaphragm M, the valve being arranged to either admit air from the pressure chamber K to a conduit N leading to the pneumatics, or to connect such conduit N to the open air.

In practice it has been found that when the music sheet E with its larger openings is used, under the same pressure requisite when using the two-bank music sheet, with its comparatively small openings, that there is not a sufficiently expeditious venting of the conduits I and the chambers beneath the diaphragms M. I therefore provide in addition to the usual vents or bleed-openings O in such chambers, additional bleed-openings P, which are opened and closed by the valve Q, pivoted to the valve box. The valve is provided with an upstanding piece R, to the end of which is secured one end of a spring S having its other end secured to the valve box. Loosely connected to the end of the upstanding piece R, is a screw-threaded rod T, having a nut U, against which the piece R bears. At its other end the rod T is eccentrically connected to a rock-shaft V passing through

the side of the trackerboard casing A, and having at its inner end a finger-piece W. The valve Q is held open against the tension of the spring by the friction of the rock-shaft 5 in its bearings, or a catch (not shown) may be provided for the finger-piece W. The various chambers, as that in box A and the chambers K in the valve boxes, are supplied with air pressure in the usual way and of course 10 the invention can be applied where tension instead of pressure is used.

In operation, when it is desired to use a multiple bank music sheet, the valve Q is moved, as shown in Fig. 1, to close the additional bleed-opening P. When it is desired 15 to use the music sheet E, the valve is raised by shifting the finger-piece, thus furnishing an additional vent through the bleed-opening P, the two openings serving to promptly and 20 efficiently relieve any residual pressure in the tubes G and conduits I, thus enabling the valve M to operate with the requisite speed.

I do not wish to be limited to the use of 25 the precise mechanism shown, as it is obviously capable of much variation without departing from the spirit of my invention.

I claim:—

1. In a pneumatically actuated valve mechanism, the combination of a chamber, 30 a valve a diaphragm carrying the valve arranged to be operated by pneumatic tension in such chamber, a conduit leading thereinto, bleed-openings in the walls thereof, and a valve for closing one of such openings.

2. In a pneumatically actuated valve mechanism, the combination of a chamber, 35 a valve a diaphragm carrying the valve arranged to be operated by a pneumatic tension in such chamber, a conduit leading thereinto, bleed-openings in the walls thereof, a valve for closing one of such openings, and mechanism for actuating such valve.

3. A pneumatic having a controlling duct 40 or connection, two bleed holes, and means for opening and closing one of them.

4. A pneumatic having a controlling duct or connection, two bleed holes, means for opening and closing one of them, said means comprising a movable valve, and connections for actuating the valve from a distance. 50

5. In combination with a tracker, a tracker duct, and a pneumatic connected with said duct, said duct having two bleed holes and a valve for one of them.

6. In combination with a tracker, a tracker duct, and a pneumatic connected with said duct, said duct having two bleed holes and a valve for one of them, and mechanical connections from the vicinity of the tracker for opening and closing the bleed hole valve. 55

7. In combination, a tracker having two sets of tracker ducts, a pneumatic connected with one duct of each set, and provided with two bleed holes, and means for opening and closing one of them. 60

8. In combination, a tracker having two sets of tracker ducts, a pneumatic connected with one duct of each set, and provided with two bleed holes, and a valve for one of the 70 said bleed holes having connections for actuating it to change the amount of bleed at will.

9. A pneumatic having a controlling duct or pneumatic connection, one or more bleed holes for the pneumatic, and adjustable 75 means for varying the leakage from the bleed hole or holes, said means having two definite limits of adjustment for providing two definite rates of bleeding or leakage, and mechanical connections for giving the said 80 means either of the two said adjustments and thereby providing either of two definite rates of leakage or bleeding.

In testimony whereof I have signed this specification in the presence of two subscribing witnesses. 85

RICHARD J. PRETTIE.
